UNITED STATES PATENT OFFICE

2,062,382

APPARATUS FOR SATURATING MATERIAL

John H. Weller, Narberth, Pa., assignor to The Barber Asphalt Company, Philadelphia, Pa., a corporation of West Virginia

Application May 18, 1932, Serial No. 611,956

2 Claims. (Cl. 91—32)

This invention relates to the improvement in an apparatus for saturating material and more particularly for saturating fabric or felt material in the strip.

The apparatus, in accordance with this invention, while adaptable for the saturating of any material with any substance with which it is to be saturated, will be found more especially advantageous in the saturation of felt for use in the production of composition roofing, such as comprises a felt base saturated with a bitumen, as asphalt, and in certain cases finally surfaced with granular material as slate, glazed granules, or the like. Since the apparatus embodying this invention lends itself to the saturation of felt in connection with the production of composition roofing, the invention will be described illustratively in such connection, without, however, in any wise limiting the invention or its adaptability to the saturation of other materials with other substances for whatever purpose the saturated materials may be intended.

In, for example, the saturation of felt with a bituminous substance, as asphalt, as heretofore effected, the felt in a strip has been led through a saturating tank containing a supply of asphalt heated to render it desirably fluid. The flooded felt, on leaving the saturating tank and carrying the hot asphalt, has customarily been passed through a set of squeeze rolls for the removal of excess asphalt, and then festooned to permit the asphalt saturant to cool. The cooling has been effected at atmospheric temperature and the passage through the squeeze rolls on leaving the saturating tank has been essential in order to avoid gumming up of the festoon rolls or bars by excess of saturant.

The saturated felt prepared by methods heretofore known has not proved entirely satisfactory, primarily because of incomplete saturation due to the removal of too much of the saturant by the action of the squeeze rolls, which not only act to remove excess saturant, but due to the highly fluid condition of the saturant carried by the felt on its passage through the squeeze rolls, the squeeze rolls act more or less as a wringer and leave in the felt insufficient saturant to completely fill the voids in the felt. In composition roofing where the felt base is incompletely saturated, or, in other words, where there are voids in the felt base, the life of the roofing is deleteriously affected, since in the course of time moisture is enabled to enter the base to its ultimate, rapid deterioration. An incompletely saturated base is further disadvantageous in con-

nection with the manufacture of composition roofing, since where the base is insufficiently saturated, more coating material, which is more expensive than the saturating material, is required than were the base completely saturated.

Now, in accordance with this invention, an apparatus is provided whereby fabric or felted material, as, for example, felt, may be completely saturated and voids eliminated.

The operation of the machine of this invention, involves subjecting the material to be saturated to a bath of saturant heated to render it desirably fluid and ultimately cooling as by the usual festooning. The flooded material however, on leaving the saturating bath and before it is ultimately cooled, is passed through an area or chamber at a suitable temperature such that the material will fully absorb the saturant with the elimination of voids. The use of squeeze rolls is avoided and the flooded material on leaving the saturating bath is merely subjected to the action of wiper bars or rolls which are adjusted to leave such an excess of saturant on the surfaces of the material as will be substantially absorbed into the material in the absorption chamber.

The apparatus embodying the invention will, it is believed, be clearly understood from the following detailed description of the apparatus and of its operation, all with reference to the accompanying drawing in which a preferred form of apparatus, in accordance with this invention, is diagrammatically shown.

In the drawing, A indicates a saturating tank containing a body of asphalt B maintained in a desirably fluid condition by heating in any suitable well known manner to a temperature of, say about 400° F. C indicates an absorption chamber which may be formed at the discharge end of the saturating tank by means of a partition D, or which may, if desired, be a separate chamber. The chamber C provides an area or chamber in which the material saturated in tank A is afforded time to fully absorb the saturant with the elimination of voids. E indicates any usual and well known festooning or looping mechanism equipped with the usual feed rolls x and a rider roll y.

The saturating tank A is provided with suitable driven rolls F and guide rolls G about which a strip of, for example, felt H, to be saturated, is led through the body of asphalt B in the tank and becomes flooded therewith. Between the reaches of the strip of felt, in its extension from the driven rolls F to idle rolls G, are positioned scrap-

ers I which act to remove excess asphalt from the surfaces of the strip prior to its passage successively from the body of asphalt B over the successive driven rolls F.

5 Ahead of the driven roll F, over which the flooded strip passes on finally leaving the body of asphalt B, a pair of wiper rolls or bars j, j are positioned and between which the flooded strip passes. The rolls or bars j, j are adjusted so 10 that they will remove from the surfaces of the strip such excess asphalt as will not be absorbed by the strip in its passage through chamber C.

The flooded strip on leaving the saturating tank A passes through the absorption chamber C in a 15 sinuous path over rolls K and L, each of which is driven from any suitable source of power through shaft M and gearing N. The absorption chamber C is maintained at a temperature sufficient to maintain the asphalt on the surfaces 20 of the strip in a fluid condition enabling its absorption into the voids in the body of the strip.

The desired temperature may be the same or above or below the temperature of the saturating water and may be, for example, about 300° F. 25 (or say within the range of 200°-400° F.), and may be maintained in the absorption chamber C through steam heating of the rolls K and L, or sufficient heating may be obtained by conduction through the partition D from the saturating 30 chamber, or the chamber C may be insulated and sufficient temperature obtained by radiation of heat from the flooded strip.

On leaving the absorption chamber, the strip is lead to any usual form of festooning mechanism 35 in which it is formed into loops or festoons P and permitted to finally cool under the influence of room temperature or in a stream of cooled air, or in any other well known manner.

In connection with the apparatus above described, it may be noted that the saturating tank 40 may be of any well known type. Thus, for example, the saturating tank may be in accordance with that described in United States Letters Patent No. 1,698,253. Likewise, the festooning mechanism may be of any well known type such 45 as, for example, that described in detail in United States Letters Patent No. 1,549,743.

It will now be observed that the apparatus, in

accordance with this invention, involves in combination essentially a saturating tank, an absorption chamber, and a festooning mechanism for finally cooling, the absorption chamber being maintained at a temperature such that the saturant carried by the flooded material and especially on the surfaces thereof will be maintained fluid for absorption into the body of the material. 5

It will be appreciated that it is not intended that this invention shall be limited to the details of the apparatus as above described, since it is appreciated that various modifications in the apparatus may be made without departing from the scope of the invention, which, as has been indicated, may be used in connection with the saturation of 10 various materials, with various saturants, for various purposes. 15

What I claim and desire to protect by Letters Patent is:

1. Apparatus for saturating strip material, including in combination a saturating tank adapted to contain a body of saturant maintained in a fluid condition by heat, an absorption chamber adapted to receive the flooded strip as discharged from the saturating tank and to maintain it 25 out of contact with the body of saturant, means for passing a flooded strip through the absorption chamber in a sinuous path, a festooning mechanism adapted to receive the strip from the absorption chamber, and means operative to partially remove excess saturant from the surface 30 only of the strip prior to its entering into the absorption chamber.

2. Apparatus for saturating strip material, including in combination a saturating tank adapted 35 to contain a body of saturant maintained in a fluid condition by heat, an absorption chamber adapted to receive the flooded strip from the saturating tank and to maintain it out of contact with the body of saturant, means for maintaining 40 an elevated temperature in the absorption chamber, festooning mechanism adapted to receive the strip from the absorption chamber, and means for partially removing excess saturant from the surface only of the strip in its passage to the 45 absorption chamber.

JOHN H. WELLER.
